UNITED STATES PATENT OFFICE

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS

CURTAIN FIXTURE

Application filed May 21, 1930. Serial No. 454,245.

This invention relates to curtain fixtures, having reference mainly to curtain supports known as the "pull cord" type, wherein mating right and left sections of the curtain or portière are suspended from a rod and are drawn together or apart at their upper ends by a cord trained over guide pulleys or sheaves in or on the rod, said cord being attached to and operating a pair of master hanger slides from which the upper ends of the inner marginal sections of the two curtains are suspended. The invention also has reference to an improved form of rod designed to afford increased stiffness and rigidity, which is capable of application generally to any type of curtain fixture.

Among the objects of the invention are, to provide an improved form of curtain rod of the hollow C-type affording increased strength and rigidity, to provide in association with such a rod, an improved system or arrangement of curtain suspending and operating devices which may be so mounted in the rod as to permit the curtains or portières to be drawn apart approximately the full length of the rod and without any interference between the hanger slides and the cord guide sheaves and their carriers, to provide a rod of the type referred to which, where considerable length is required, may be made in sections having a flush meeting joint or joints rigidly connected by a snugly fitting internal splice, and wherein the presence of the splice presents no interference with the free running of the hanger slides.

Still other objects and attendant advantages of the invention will be apparent to persons skilled in the art as the same becomes better understood by reference to the accompanying drawings, in which I have illustrated one practical embodiment of the invention, and wherein—

Fig. 1 is a front elevation of the fixture showing the same mounted on a window frame.

Fig. 2 is an enlarged horizontal longitudinal section, taken on the line 2—2 of Fig. 1, and broken out between its ends.

Fig. 3 is a vertical transverse section through the rod, splice, and one of the master

hanger slides, taken on the line 3—3 of Fig. 2.

Fig. 4 is a vertical transverse section through the rod and one of the follower hanger slides, taken on the line 4—4 of Fig. 2.

Fig. 5 is a perspective elevation of one of the master hanger slides.

Fig. 6 is a perspective elevation of the splice employed in a sectional rod.

Fig. 7 is a perspective elevation of the sheave carrier and sheave located at the left hand end of the rod, in Figs. 1 and 2.

Fig. 8 is a perspective elevation of the sheave carrier and sheave located at the right hand end of the rod, Figs. 1 and 2.

Referring to the drawings, 10 designates each of a pair of straight hollow curtain rod sections that are supported at their outer ends on brackets 11 and at their inner or meeting ends are rigidly connected and supported by an internal hollow splice 12, which construction permits the two sections 10 to be made of equal cross sectional sizes and to meet in a flush joint 13. The rod is of the generally "flat" or C-type, but is modified by being made of somewhat greater width, and the top and bottom walls of the rod are pressed inwardly in the form of hollow longitudinal ribs 14, as clearly shown in Figs. 3 and 4. The purpose of these ribs is two-fold. In the first place, they considerably increase the strength and rigidity of the rod and enable the latter to resist a downward bowing or bending tendency under the weight of the curtain or portière, and in the second place, they create in effect a double or twin channel rod consisting of an outer or wider channel 15 and an inner or somewhat narrower channel 16. The rear wall of the rod has the usual central longitudinal slot of rods of the C-type, and in the rear channel 16 are mounted a group of curtain suspension slides, including a pair of master slides to which the inner upper corners of the curtains C are attached.

First describing the follower suspension slides, one of which appears in side elevation in Fig. 4, this slide comprises a roller 17 that travels in the bottom groove of the rear channel 16, the roller being of such diameter that its upper portion enters the upper groove of

65

100

the channel 16 so that it is sustained laterally by the walls of said upper groove and thus maintained in a vertical position. Integral with the roller 17 is a short lateral hub or boss 18 that extends through the slot in the rear side of the rod but is out of contact with the edges of said slot, and on the outer end of the boss or hub 18 is a flange 19 of sufficient diameter to overlap the edges of the slot. The 10 roller 16 and its boss 18 are fast on a central spindle 20, which latter projects sufficiently beyond the boss 18 and its flange 19 to form a support for hanger arm 21 that is loosely mounted and suspended thereon, the lower 15 end of the hanger arm being stitched or otherwise secured to the curtain C. The purpose of the flange 19 is to prevent the hanger arm 21 from rubbing against the lower portion of the rear wall of the rod as the curtains 20 are drawn lengthwise of the latter, avoiding the friction and wear that would result from such rubbing contact.

In the present instance, I have shown the curtain support as adapted for the application thereto of a pull cord mechanism for operating the curtains; the structural features of the rod itself being well adapted for the application of a pull cord mechanism and permitting the free operation of the latter without any interference with the cord guiding and supporting sheaves and their carriers in the ends of the rod, or with the internal splice where the latter is employed in a sectional rod. Describing first the 35 sheave carrier and sheave at the left hand end of the rod that supports and guides the intermediate portion of the cord, and referring particularly to Fig. 7, this comprises a U-shaped sheave carrier, the parallel flat side 40 walls 22 of which are connected at their inner ends by an integral bridge 23. In and between the side walls 22 is journaled the sheave 24, and the outer end of one of the side walls 22 is formed with a laterally bent 45 stop flange 25. As shown in Fig. 2, this sheave carrier and sheave is fitted into one end of the front channel 15 of the curtain rod, the stop flange 25 abutting against the end of the front wall of the rod, and thus 50 holding the sheave carrier in place against the inward pull of the cord when the curtains are operated.

The sheave carrier and sheave at the opposite or right hand end of the rod is shown 55 in detail in Fig. 8 and also comprises a generally U-shaped sheave carrier, the parallel flat side walls 26 of which are connected along one longitudinal edge thereof by a bridge 27. In and between the side walls 26 are journaled outer and inner guide sheaves 28 and 29 respectively, the outer sheave 28 being located sufficiently higher than the inner sheave 29 to permit the upper limb of the cord, which passes over the sheave 28, to pass 60 above the lower limb which is guided over

the sheave 29. One of the side walls 26 is severed transversely and bent outwardly to form a stop 29' which, as shown in Fig. 2, abuts against the end of the rod and prevents the sheave carrier from being displaced inwardly under the pull of the cord. The bridge portion 27 of the sheave carrier is, of course, cut away below the outer portions of the sheaves 28 and 29 to permit the limbs of the cord to depend therefrom, as shown 75 in Fig. 1.

The pull cord is designated by 30, and adjustably attached to the two limbs thereof, which extend through the rod, are the master curtain suspension slides designated as entireties by 31 and 32. These master slides are structural duplicates, except as to the feature of a curtain overlap support on one of them hereinafter referred to.

Describing the master slide 31, which appears in horizontal section in Fig. 2 and in perspective view in Fig. 5, 31' designates a flat plate, in the upper portion of which are mounted a pair of rollers 32 which are structurally identical with the rollers 17 of the follower suspension slides, previously described, and ride in the bottom groove of the rear channel 16 of the rod; the plate 31' having the same loose mounting on the spindles of the rollers as above described in 90 connection with the hanger arms 21 of the rollers 17. The lower portion of the plate 31' is forwardly offset and formed with holes 33 for the attachment of the upper edge of the curtain thereto. A tongue 34 is cut and bent 100 forwardly on an incline from the plate 31' as clearly shown in Fig. 2, and this tongue is formed with a slot 35 for the passage of the cord 30 therethrough; it being understood that one limb of the cord 30 is engaged with the tongue 34 of the slide 31, while the other limb of the cord is similarly engaged with the tongue 34 of the other slide 32. In the plate 31 adjacent to the base of the tongue 34 is a tapped hole, through which is entered 110 a clamp screw 36, the free end of which is adapted to bite the cord between the inner end of the screw and the forward end wall of the slot 35, whereby the slide is securely attached to the cord, but may be readily adjusted 115 lengthwise of the latter by backing off the screw 36, adjusting the slide to a new position on the cord, and retightening the screw 36.

As above stated, the two master slides 31 and 32 are structural duplicates to the extent above described; but where an overlap of the meeting edges of the curtains is desired, one of the slide plates such as 31', has attached thereto a forwardly offset arm 37 that projects 125 toward and overlaps the opposite master slide when the curtains are fully drawn together, and is formed with holes 33' for attachment to the curtain.

The splice 12, which is employed in a sec- 130

tional rod, preferably has the hollow **C**-shaped cross-sectional form illustrated in Fig. 6, and is snugly telescoped within the meeting end portions of the front channels 15 of the main rod sections 10. By locating this splice in the front channels of the rod sections, it presents no obstruction to, or interference with, the free movement of the suspension slides, and it also provides a stiffer and stronger rod than a single integral rod of the same length, cooperating with the ribs 14 to provide a very stiff and rigid long rod that will support curtains or portières without any sagging or bending.

From the foregoing it will be seen that by locating the sheave carriers and sheaves in the ends of the front channel of the rod, and also the splice 12 (where the latter is employed) in the front channel, these parts present no interference with or obstruction to the free sliding movement of the curtain suspension slides, enabling the latter to be drawn outwardly to a greater extent than if the sheave carriers, and suspension slides were all located in a single channel. Moreover, since the master slides to which the cord is clamped operate in and through the rear channel 16 of the rod, while the hollow splice 12 is located in the front channel 15, the cord is maintained out of rubbing contact with the splice so that it does not become chafed and worn by the latter.

By the expression "front channel" as used herein, I mean the interior portion of the rod lying between the front wall and the internal ribs, and by the expression "rear channel" I mean the interior portion of the rod lying between said ribs and the longitudinally slotted rear wall.

The curtain suspension slides herein shown and described are not specifically claimed herein, since they form the subject matter of an application filed simultaneously herewith, Serial No. 454,246. Also, the sheave carriers and sheaves that are slidably mounted in the ends of the rods and shown in detail in Figs. 7 and 8 are not specifically claimed herein, since they form the subject matter of another application filed concurrently herewith, Serial No. 454,248.

I claim:

1. A hollow sheet metal curtain rod of **C**-form in cross section formed with hollow internal ribs on and disposed lengthwise of its top and bottom walls respectively.

2. A hollow sheet metal curtain rod comprising duplicate rod sections each of **C**-form in cross section formed with internal ribs on and disposed lengthwise of the top and bottom walls thereof respectively, and a splice telescoped within the adjacent portions of said rods between said ribs and an opposite wall of the rod.

3. A hollow sheet metal curtain rod comprising duplicate rod sections each of **C**-form

in cross section formed with internal ribs on and disposed lengthwise of the top and bottom walls thereof respectively, and a hollow splice of **C**-form in cross section telescoped within adjacent portions of said rods between said ribs and the front wall of the rod.

4. A hollow sheet metal curtain rod formed with a solid front wall, a longitudinally slotted rear wall, and internal ribs extending lengthwise of its top and bottom walls forming front and rear longitudinal channels, in combination with curtain hanger slides mounted to travel in said rear channel, cord guide sheaves mounted in the ends of said front channel, a draw cord extending through said rod and guided over said sheaves, and means for connecting said pull cord to the innermost two slides.

5. A hollow sheet metal sectional curtain rod formed with a solid front wall, a longitudinally slotted rear wall, internal ribs extending lengthwise of its top and bottom walls forming front and rear longitudinal channels, and a hollow splice of **C**-form in cross section telescoped within adjacent portions of the front channels of the rod sections, in combination with curtain hanger slides mounted to travel in said rear channel, cord guide sheaves mounted in the ends of said front channel, a draw cord extending through said rod and guided over said sheaves, and means for connecting said pull cord to the innermost two slides.

6. A hollow sheet metal curtain rod comprising a front wall, top and bottom walls, and a longitudinally slotted rear wall, said bottom wall being formed with a substantially central hollow upstanding longitudinal rib.
